COMBINED DISPLAY AND DISPENSING RACK

Mitchell Silverstein, 1452 Keystone,
River Forest, Ill. 60305

Filed Mar. 11, 1966, Ser. No. 1,416

Term of patent 14 years

(Cl. D80—10)

The broken line representation of a package in FIGURES 1 and 2 is for purposes of illustration only.

I claim:

The ornamental design for a combined display and dispensing rack, substantially as shown and described.
